LOADING CHUTE

Filed July 14, 1927

UNITED STATES PATENT OFFICE.

FRANK DE ROOS, OF SPRINGFIELD, SOUTH DAKOTA.

LOADING CHUTE.

Application filed July 14, 1927. Serial No. 205,750.

My invention relates to loading chutes and it is my object to provide a chute of the type which is hinged to the rear edge of a truck floor and adapted to swing upwardly to 5 form a part of the end gate of the truck.

More specifically, it is my purpose to provide such a chute having a hinged portion which is extensible to lengthen the chute to reach the ground at a proper incline, said 10 hinged portion being adapted to swing by gravity to a closed position relative to the remainder of the chute when the latter has been swung upwardly to its vertical position, serving as an end gate.

15 A further object of my invention is to provide such a chute having an intermediate support hinged in such a manner as to fold in unison with the folding extension.

With these and other objects in view, my 20 invention consists in the construction, arrangement and combination of the various parts of my device, whereby the objects contemplated are attained, as hereinafter more fully set forth, pointed out in my claims, 25 and illustrated in the accompanying drawings, in which:

Fig. 1 is a side elevation of my invention attached to a truck, the floor of which is shown in section.

30 Fig. 2 is a vertical, sectional view through the same in its closed position, serving as an end gate.

Fig. 3 is an enlarged end elevation of the 35 upper portion of the device when serving as an end gate, showing its attachment to the truck box.

Fig. 4 is a detail, sectional view illustrating the attachment of the sides of the chute.

Fig. 5 is an inverted plan view of the 40 chute.

Fig. 6 is a detail, sectional view illustrating the hook by means of which the chute side members are stored within the truck box when not in use.

45 I have used the reference character 9 to indicate generally the floor of a truck, to the rear extremity of which is hinged the chute of my invention.

The chute comprises a bottom member A, 50 detachable side members B, a hinged extension C and a hinged support D.

The bottom member A and the hinged extension C comprise pairs of side rails 10^a and 11, respectively, spaced apart and se-

cured together by floor slats 12 and hinged 55 together by means of a rod 13, which extends through the overlapping ends of the rails 10^a and 11, respectively. The rails 11 are spaced more closely together than the rails 10^a and are received between the latter. The 60 support D comprises a pair of legs 14, pivoted upon the rod 13 and secured together at their other ends by a cross member 15. An intermediate cross member 16 is employed to space apart the legs 14 at their 65 inner ends and to more securely brace the whole structure of the support.

A pair of yokes 17 are secured to the outer faces of the rails 10^a near their outer ends, 70 one end of each yoke being secured upon the rod 13, which is headed at one end as at 18 and provided with a threaded nut 19 at its other end. A pair of similar yokes 20 are secured to the remote ends of the rails 10^a. 75

To the inner ends of the rails 10^a are secured a pair of hinge straps 21, terminating in loops 22 which receive a hinge rod 23. Co-acting hinge strap 24, provided with loops 25, receive over the rod 23, are secured 80 to the bottom 10 of the truck.

The detachable side members each comprises a pair of spaced posts 27, connected by spaced longitudinal bars 28. A pair of tongues 29 are secured to the inner faces of 85 the posts 27 at their lower ends and the adjacent portions of the posts are recessed as at 30 so that the tongues 29 may be inserted between the yokes 17 and the rails 10^a. (See 90 Figs. 1 and 4.)

When the device is to be used as a chute, it is hinged downwardly to the position shown in Fig. 1, the extension being swung to alignment with the bottom member A. It may be noted at this point that the adjacent floor slats 12 at the connected ends of the members A and C, respectively, are so positioned as to abut one another when the extension has been brought to its aligned position relative to the bottom member A. 100 Thus these floor slats act as limiting stops. In order to support the loads to which the chute will be subjected, however, the support D is provided and is of such a length as to just reach the ground when swung to a 105 vertical position with the end of the extension C resting upon the ground. Since the natural position of the support D would be

to hang downwardly and there is no longitudinal movement possible in the chute while the truck is standing still, the user of the device will never be bothered with the support losing its correct vertical position.

When the device is to be folded up to serve as an end gate, the side members B are first removed and stored within the truck box and the operator then simply grasps the 10 under side of the bottom member A and pushes it upwardly to a vertical position. As the bottom member swings upwardly, the extension C and the support D will assume depending positions, causing them to fold 15 within the rails 10^a, as shown in Fig. 2. Hooks 31, secured to the rails 10^a, are adapted to engage with screw eyes 32 in a cross member 33 of the truck box for retaining the device in the closed position.

20 Hooks 34, secured to the inner faces of the rails 10^a, are adapted to engage eyes 35 in the rails 11 to retain the extension C securely against flopping while the truck is in motion. The extension C in turn incloses, 25 between it and the bottom member A, the support D.

The advantages of my device reside in the simplicity of construction, the semi-automatic folding feature, and the usual advantages of a hinged combination chute and end gate. The side members B are stored in the truck box by placing the hooks 50, shown in

Figs. 6 and 1, respectively, over one of the side rails 51 of the truck box.

Some changes may be made in the construction and arrangement of the parts of my invention without departing from the real spirit and purpose of my invention, and it is my intention to cover by my claim, any modified forms of structure or use of mechanical equivalents, which may be reasonably included within their scope.

I claim as my invention:

In combination with a truck box, a chute bottom hinged to the rear extremity of the 45 bottom thereof and adapted to swing upwardly to a substantially vertical position, said chute bottom including side rails, an extension hinged at the outer end of said chute bottom, and a support hinged to the chute 50 bottom on the same axis as the extension, both support and extension including side rails, the side rails of the chute bottom, the support and the extension being provided in pairs arranged within each other so as to 55 fold together with their edges positioned substantially in common planes, the extension and support being adapted to swing downwardly toward said positions as the chute bottom is raised.

Signed this 27 day of June, 1927, in the county of Woodbury and State of Iowa.

FRANK DE ROOS.
